DIRECTION SENSING DEVICE

Harry C. May, East McKeesport, Pa., assignor to
Westinghouse Air Brake Company, a corpora-
tion of Pennsylvania

Application July 26, 1949, Serial No. 106,863

4 Claims. (Cl. 137—609)

1

This invention relates to a direction sensing device and more particularly to such a device for use as a directional interlock valve device in reversible engine control apparatus.

The principal object of the present invention is the provision of an improved directional interlock valve device of the type disclosed in United States Patent No. 2,459,883, issued to Cecil S. Kelley on January 25, 1949.

The above-mentioned patent discloses a directional interlock valve device which comprises valve means adapted to be actuated to either one of two positions for connecting a delivery pipe to either one or the other of two control pipes, respectively. The valve means is actuated through certain linkage by movement of a shoe in frictional engagement with such as an engine crank shaft in rotation to position said valve means in either of two positions according to the direction of such rotation. A fluid pressure piston is provided for moving the shoe into engagement with the shaft, and a return spring is provided for returning said shoe and piston to respective repose positions. For locking the valve means in either of the two positions, a pin secured to the casing of the device projects into one or the other of two spaced apart recesses formed in a rib of the shoe when same assumes its repose position. Contingent upon severe vibration, the shoe may bounce free of the locking pin and allow the valve means to assume an undesired neutral position. In view of this, it is another object of the invention to provide a directional interlock valve device which comprises improved means for locking the valve means in position.

A further object of the invention is the provision of means to limit the force exerted by the shoe on the shaft when held in contact therewith by the piston.

A still further object of the invention is to provide an arrangement whereby sudden undesired pressure impulses of short duration which may get into the pipe which conveys working fluid to and from the fluid pressure shoe actuating piston, are prevented from causing accidental operation of said piston.

Other objects and advantages will become apparent from the following detailed description of the invention.

2

In the accompanying drawing, the single figure is a sectional view of a directional interlock valve device, embodying the invention.

Description

Referring to the drawing, the directional control device comprises a casing 1 having two oppositely arranged, coaxially aligned valve assemblies 2 and 3 for controlling communication respectively, between a delivery pipe 4 and control pipes 5, 6.

Both of the valve assemblies 2 and 3 may be alike, and for sake of brevity, identical elements of the two assemblies will be given the same reference numerals in the drawing, with the reference numerals pertaining to the elements of assembly 3 primed to distinguish over the elements of assembly 2 to avoid confusion in subsequent description of operation of the device.

For sake of illustration, schematically, the valve assemblies 2 and 3 may comprise respectively, a poppet valve 7, 7' disposed in a chamber 8, 8' formed in the casing 1. The poppet valve 7, 7' is attached to an actuating stem 9, 9' which is slidably disposed in a casing bore 10, 10' through the medium of a connecting stem 11, 11'. A valve seat is formed in the casing encircling one end of the bore 10, 10' to accommodate the valve 7, 7' which, when seated thereon, closes the chamber 8, 8' to said bore. A compression spring 12, 12' is disposed in the chamber 8, 8' and arranged to urge the valve 7, 7' toward its seat. A removable cap 13, 13' in screw-threaded attachment with the casing is provided to retain the spring 12, 12' and to allow for removal and insertion of the valve 7, 7' and attached stems 9, 9' and 11, 11'. The stem 9, 9' projects outwardly through the opposite end of the bore 10 for engagement with an actuating element 15 slidably mounted in the casing.

In the assembly 2, the chamber 8 is connected to the forward control pipe 5 and the bore 10 is constantly open to the bore 10' in assembly 3 and to the delivery pipe 4 by way of such as a passage 4a formed in the casing. In the assembly 3, its chamber 8' is connected to the reverse control pipe 6.

When the actuating element 15 is moved in the direction of the assembly 2, the stem 9 will be displaced inwardly of the bore 10, and thereby

cause unseating of the poppet valve 7 against action of the spring 12 and opening the chamber 8, hence the control pipe 5, to the bore 10, hence to the delivery pipe 4. At the same time, such movement of the element 15 will allow, in assemblage 3, the spring 12' to seat the poppet valve 7' thereby closing off the bore 10', hence delivery pipe 4, from the chamber 8', hence from the control pipe 6. Upon return movement of the actuating element 15 in the direction of the valve assemblage 3 to the position in which it is shown in the drawing, through resultant movement of the stem 9', the poppet valve 7' will be moved to its open position in which it is shown in the drawing, thereby opening the chamber 8', hence the control pipe 6, to the bore 10', hence to the delivery pipe 4. At the same time such movement of element 15 will, in valve assemblage 2, allow the spring 12 to move the poppet valve 7 to its closed position in which it is shown in the drawing, thus closing off the chamber 8, hence the control pipe 5, from the bore 10, hence from the delivery pipe 4. Openings 20 in the casing are provided for slidably guiding the actuating element 15.

To sense the direction of rotation of such as reversible engine crank shaft 25, for example, a friction shoe assemblage 26 is provided. The shoe assemblage 26 may be moved into engagement with the shaft 25, which, when in rotation will urge the shoe assemblage 26 either toward the valve assemblage 2 or toward the valve assemblage 3, according to the direction of such rotation.

The shoe assemblage 26 is loosely connected at 27 to one end of an operating stem 28 which is rockably connected at its opposite end to a shoe actuating piston assemblage 29 to allow for sidewise movement of the friction shoe assemblage when in engagement with the rotating engine crank shaft 25. To define the limit for such sidewise movement, the shoe assemblage 26 may engage either one of two spaced apart casing shoulders 35, 36 according to the direction of the movement. The stem 28 extends through an opening defined by a rounded shoulder 37 formed in the actuating element 15, thereby operatively connecting the shoe assemblage 26 to said actuating element. During sidewise movement of the shoe assemblage 26, resultant rocking movement of the stem 28 is translated into sliding movement of the actuating element 15 through engagement of said stem with the rounded shoulder 37. When the shoe assemblage 26 is in position in engagement with the shoulder 35, the actuating element 15 will be in the position in which it is shown in the drawing, holding the poppet valve 7' unseated against action of the spring 12', with the poppet valve 7 seated. Conversely, when the shoe assemblage 26 is in position in engagement with the opposite shoulder 36, the actuating element will be in a position opposite to that in which it is shown in the drawing, holding the poppet valve 7 unseated against action of the spring 12, with the poppet valve 7' seated.

To hold the actuating element 15, and thereby the stem 28 and shoe assemblage 26 in one or the other of their corresponding opposite positions described, above, an improved locking means is provided which comprises a tapered locking pin 40 reciprocably fitting in an accommodating casing bore 41 for slidable engagement with a similarly tapered locking element 42 attached to and carried by the actuating element 15. When the actuating element 15 assumes the position in 75

which it is shown in the drawing, it may be locked therein through engagement between coincident faces 43, 44 of the tapered locking pin 40 and element 42, respectively. When the actuating element 15 assumes the position opposite to that in which it is shown in the drawing it may be locked in such position through engagement of opposite faces 45, 46 of stem 40 and element 42, respectively. The stem 40 is urged into locking engagement with the element 42 by a compression spring 47 disposed in an atmospheric chamber 48 at one side of an unlocking piston 49 attached to said stem. The tapered faces 43, 45 and 44, 46 of stem 40 and element 42 respectively, act to urge the actuating element 15 toward the position in which it is desired to lock same when said pin is urged by spring 47 into engagement with said element 42. The unlocking piston 49 is slidable within an accommodating bore 50 in the casing. Upon supply of fluid under pressure to a chamber 51 at one side of the piston 50, said piston may be caused to move in the direction of chamber 48 against action of the spring 47 to move the stem 40 out of locking engagement with the element 42, thereby freeing the actuating element 15 for slidable movement. Upon subsequent release of fluid under pressure from the chamber 51, the spring 47 will return the piston 49 to the position in which it is shown in the drawing, defined by contact with an annular seat rib 53, thereby moving the stem 40 into locking engagement with the element 42. One purpose of the seat rib 53 is to reduce the effective area which will be exposed to the pressure of fluid in the chamber 51 when the piston 49 is seated thereon, so that when once unseated, the increased area thereby presented to such pressure will cause snap acting movement of the piston to an opposite position in engagement with an annular resilient seat washer 55, thereby quickly unlocking the actuating element 15 to prevent drag between the stem 40 and element 42 and thereby prevent excessive wear on these parts. An operating control pipe 60 is connected to the chamber 51 for conveying fluid under pressure thereto and therefrom.

The piston assemblage 29 may comprise a piston follower element 70 which is slidably mounted in a suitable bore 71 in the casing. The stem 28 is slidably and rockably connected at its one end to the follower element 70 through the medium of an attached disk-shaped element 72 slidably disposed within an accommodating bore 73 opening into said element 70 centrally thereof. The element 72 is retained in the bore 73 by a retaining ring 74, which is removably secured to the follower element 70. The element 72 is provided with a radius about its periphery in slidable line contact with the wall of the bore 73 to allow for pivotal movement of the respective end of the stem 28 during sidewise movement of the shoe assemblage 26 at the opposite end of said stem. The end of the stem which is attached to the element 72 is of reduced cross section for projection through the retaining ring with clearance to allow for the above mentioned pivotal movement. A compression spring 75 is arranged to seat at its one end against the piston follower element 70, an annular groove 76 being formed in said element 70 to locate the respective end of said spring. The opposite end of the spring 75 seats on a spring seat washer member 78 carried by the stem 28, an annular collar 79 being formed member 78 is urged by said spring. The spring 75 urges the stem 28 in a direction away from the follower element 70 and toward the crank

shaft 25. In the position of the piston follower element 29 shown, the element 72 of the stem 28 is in engagement with the retaining ring 14, thereby defining a repose position of the shoe assemblage 26 spaced away from the crank shaft. The piston follower element 10 is urged toward the position in which it is shown in the drawing by a piston return spring 89 compressed between said element 79 and an annular shoulder 81 formed in the casing 1. The piston assemblage 29 further comprises a resilient diaphragm 85 which is clamped at its outer periphery between two portions of the casing. The diaphragm 85 is exposed to a pressure chamber 86 on its one face while its opposite face fits against a face of the piston follower element 10 which is properly contoured to accommodate the usual annular fold at the outer edge of the diaphragm which allows for movement of said follower element by said diaphragm when fluid under pressure is supplied to said chamber 86. Movement of the follower element 10 out of its repose position, in which it is shown in the drawing and which may be defined by contact of a central portion of the diaphragm with an end wall 90 of the casing, in the direction of the crank shaft 25 is limited by engagement with an annular shoulder 91 formed in the casing. The pressure chamber 86 at the one side of the diaphragm 85 is connected to a casing port and passage 92 which opens at its one end into the bore 50 in which the unlocking piston 49 is slidably disposed. The port 92 is so located that, with the unlocking piston in the position in which it is shown in the drawing, that is, seated on the rib 53, said port 92 will be in registry with a port and passage 95 extending through said piston from its peripheral edge to the atmospheric chamber 48 at its one side. Said port 92 will be opened to the chamber 51 when said piston leaves said rib and seats on the resilient seat washer 55.

Operation

Referring to the drawing, assume that the directional interlock device was last operated when the engine crank shaft was turning in its forward direction with the operating control pipe 60 now vented. All parts of the directional interlock device will have assumed the respective positions in which they are shown in the drawing. Fluid under pressure will have vented from the pressure chamber 86 by way of the passage 92, chamber 51 and the pipe 60. The piston follower element 10 will be in its repose position, with the diaphragm 85 seated against the casing end wall 90, and the unlocking piston 49 will be seated on rib 53. The locking stem 40 will be in locking engagement with the element 42, holding the actuating element 15 in position to maintain the valve 7' open, the valve 7 closed, and holding the shoe assemblage 26 in leaning engagement with casing shoulder 35. The element 72 attached to the end of the stem 28 will be seated on the retaining ring 14 attached to follower element 10, and the shoe assemblage 26 will be disposed a short distance away from the engine crank shaft 25.

Assume now that the engine crank shaft 25 is again rotating in its original or forward direction when the directional interlock device is brought into operation. Fluid will be supplied to the chamber 51 beneath the unlocking piston 49, and when the pressure of such fluid increases sufficiently, will cause said unlocking piston to snap to its opposite position seated on washer 55,

to unlock the actuating element 15. Fluid under pressure will flow from the chamber 51 through the passage 92 to the pressure chamber 86, causing deflection of the diaphragm 85 and resultant movement of the follower element 10 out of its repose position to its position in engagement with the shoulder 91. This movement of the follower element 10 out of its repose position will carry the compression spring 75 and stem 28 with it and thereby will cause engagement of the shoe assemblage 26 with the forwardly rotating crank shaft 25, and will cause the force of the precompressed spring 75 to be transmitted through the stem 28 and said shoe assemblage to said crank shaft as the element 12 of said stem is caused to unseat from the retaining ring 14 and follower element 10 engages the casing shoulder 91. It will be appreciated that the force exerted by the shoe assemblage 26 against the crank shaft 25 will be limited substantially to that resulting from the compression of the spring 75, and such force will be constant and independent of the pressure of fluid which may be supplied to the chamber 86 for effecting movement of said shoe assemblage into engagement with said shaft.

Since the shaft 25 is turning in its original or forward direction at this time, the shoe assemblage 26 will remain in engagement with the casing shoulder 35, and the actuating element 15 therefore will remain so positioned as to maintain the valve 7' open and the valve 7 closed, with the delivery pipe 4 consequently connected to the control pipe 6 and disconnected from the control pipe 5.

If, while the shoe assemblage 26 is thus in engagement with the forwardly rotating engine crank shaft 25, the pipe 60 is vented to atmosphere, the unlocking piston 49 will be moved to its seated position on the rib 53 by action of the spring 47 as pressure of fluid is reduced in the chamber 51 through release of fluid under pressure by way of the vented pipe 60. The locking stem 40 thus will be moved to its position for locking the actuating element 15 and valves 7, 7' in the position described above. When the unlocking piston 49 assumes its position seated on rib 53, the port and passage 95 in said piston will be brought into registry with the port or passage 92, allowing fluid under pressure from the pressure chamber 86 to release to atmosphere by way of the atmospheric chamber 48 at one side of said piston 49. The shoe assemblage 26 will then be carried to its retracted position disposed away from the crank shaft 25, as the diaphragm 85, follower element 10, spring 75 and stem 28 are caused by spring 80 to assume the positions in which they are shown in the drawing and in which they were previously described.

Assume that the shoe assemblage 26 is in engagement with the forwardly rotating shaft 25, with the chamber 86 charged with fluid under pressure and the actuating element 15 unlocked as previously described. Assume that while the shoe assemblage is in engagement with the shaft 25, the shaft reverses its direction of rotation from forward to reverse, for example. Upon initial turning movement of the shaft 25 in its new or reverse direction, the shoe assemblage 26 will leave the shoulder 35 and move into engagement with the shoulder 36, causing movement of the actuating stem 15 to its position for allowing the valve 7' to close and to open the valve 7, thereby connecting the delivery pipe 4 to the control pipe 5 rather than to the control pipe 6. If at this time the pipe 60 is vented, the unlocking

piston will move to cause locking of the actuating stem and valves as previously described, followed by return of the follower element 70, stem 28 and shoe assemblage to their respective repose positions as fluid under pressure releases from the chamber 86 by way of the passage 92, port 95 in the unlocking piston 49, and the atmospheric chamber 48 at one side of said piston.

The interlock valve device may again be brought into operation as aforescribed to sense the direction of rotation of the crank shaft 25 and cause positioning of the valves 1, 1' accordingly, and subsequently released as described, with the crank shaft turning initially in its reverse direction and reversing its direction of rotation back to ahead during engagement of the shoe assemblage 26 therewith in fashion similar to operation as described.

Summary

It will be appreciated that I have provided a directional interlock valve device which comprises improved means for locking the actuating element 15 and valves 1, 1' in their adjusted positions which will not be influenced by engine vibrations or the like and will maintain such positions reliably.

It will also be seen that by virtue of the fact that supply of fluid under pressure to the pressure chamber 86 is controlled by operation of the unlocking piston 49, sudden undesired pressure impulses which may leak into the pipe 60 will not cause unintentional engagement of the shoe assemblage with the shaft, since such pressure impulses, being exerted against a limited area of the piston 49 when seated on rib 53 will not produce a force sufficient to unseat said piston and allow a supply of fluid under pressure to reach the pressure chamber 86.

And still further, it will be appreciated that by virtue of the arrangement for effecting engagement of the shoe assemblage with the shaft 25, through transfer of force resultant from the precompressed spring 75, the force of said shoe on said shaft may be kept at a desired minimum and a constant value, regardless of the pressure of fluid which might be supplied to the chamber 86.

Having now described the invention, what I claim as new and desire to secure by Letters Patent, is:

1. In combination with a casing having a first chamber and a second chamber, a motion reversible member, a structure movable longitudinally into and out of engagement with said member and movable transversely by said member when in engagement therewith, actuating means responsive to supply of fluid under pressure to said first chamber to effect longitudinal movement of said structure into engagement with said member, first spring means to effect longitudinal movement of said structure out of engagement with said member upon release of fluid under pressure from said first chamber, a valve actuating element slidably mounted in said casing and operably connected to said structure for slidable movement thereby in one direction or its opposite according to direction of transverse movement of said structure, valve means operable by said valve actuating element to assume positions according to direction of sliding movement of said actuating element, stop means engageable by said structure to define two opposite positions of said actuating element, a locking pin movable into engagement with said actuating element to lock

same in either one or the other of its opposite positions, unlocking piston means operatively connected to said locking pin responsive to supply of fluid under pressure to said second chamber to disengage said locking pin from said actuating element and to uncover a port connecting said first chamber to said second chamber, and second spring means cooperative with said casing and said unlocking piston to urge said unlocking piston in the direction of said second chamber to cause engagement of said locking pin with said actuating element and to open said port to atmosphere for releasing fluid under pressure from said first chamber.

2. The combination as set forth in claim 1, including other spring means interposed between said structure and said actuating means through the medium of which the longitudinal movement of the former is effected by the latter.

3. In combination, a reversible rotatable shaft, a casing having a pressure chamber, a passage connected to said pressure chamber and a piston bore arranged radially to said shaft, a friction shoe for engaging said shaft, a piston disposed in said bore for slidable movement therein, a stem carrying said shoe at its one end and having a pivotal connection with said piston, said pivotal connection being slidable longitudinally of said piston, a spring seat element carried by said stem intermediate its opposite ends, a first compression spring abutting at its one end said piston and at its opposite end said spring seat element, urging said stem in a direction away from said piston and toward said shaft, retaining means cooperable between said piston and said stem, a second compression spring cooperable with said casing and piston for urging said piston in a direction away from said shaft to a repose position in which said stem is in engagement with said retaining means and said friction shoe is disposed a certain distance away from said shaft, means for defining said repose position, flexible diaphragm means operable in response to supply of fluid under pressure to said pressure chamber to overcome action of said second compression spring for effecting slidable movement of said piston to a shoe engaging position in which said friction shoe is held in engagement with said shaft by force of said first compression spring, stop means cooperable with said piston to define said shoe engaging position, two oppositely arranged valve structures disposed in said casing at opposite sides of said stem, a rigid valve actuating element interposed between said valve structures and slidably movable by pivotal movement of said stem to one or the other of two opposite positions to condition said valve structures accordingly, a locking stem movable into engagement with said actuating element for locking same in one or the other of said two opposite positions, third spring means urging said stem into such engagement, and unlocking piston means operatively connected to said locking stem and operable to move said locking stem in opposition to action of said third spring means for disengaging said locking stem from said actuating element, movement of said unlocking piston means in cooperation with said passage also controlling supply and release of fluid under pressure to and from said pressure chamber.

4. In combination with a casing having a first fluid pressure chamber, and a second fluid pressure chamber, a motion reversible member, structure movable longitudinally into engagement

with said member and movable by such engagement to either of two opposite transverse positions, first fluid pressure actuating means responsive to supply of fluid under pressure to said first fluid pressure chamber to move said structure longitudinally, a locking pin in locking engagement with said structure preventing transverse movement of same, second actuating means operatively connected to said locking pin and responsive to supply of fluid under pressure to said second fluid pressure chamber to move said locking pin to a position out of locking engagement with said structure, and valve means associated with said second actuating means controlling ad-

mittance and release of fluid under pressure to and from said first fluid pressure chamber.
